DESIGN FOR BARREL-BOLTS.

Specification forming part of Design No. 6,160, dated October 1, 1872.

CASE K.

To all whom it may concern:

Be it known that I, OTTO F. FOGELSTRAND, of Kensington, in the county of Hartford and State of Connecticut, have invented a Design for a Barrel-Bolt, of which the following is a specification:

The nature of my design is fully represented in the accompanying engraving, to which reference is made.

A represents the bolt proper, B its barrel, and C its staple. The parts B C are each provided with a flange, a. The front faces of the barrel and staple are rectangular in form, and

are bordered by a plain ledge. A raised ledge in scroll form extends from near each corner of said faces and cross each other near the center, as shown. The flange a is also bordered by a ledge, inside of which is scroll or ornamental work in relief.

I claim as my invention—

The design for a barrel-bolt, as shown in the drawing.
